HAIR BAND

Ernst K. Kuenstner, Milwaukee, Wis.

Application September 2, 1949, Serial No. 4,836

Term of patent 7 years

(Cl. D86—10)

To all whom it may concern:

Be it known that I, Ernst K. Kuenstner, a citizen of the United States and resident of Milwaukee, in the county of Milwaukee and State of Wisconsin, have invented a new, original, and ornamental Design for a Hair Band, of which the following is a specification, reference being had to the accompanying drawings, forming part thereof.

I claim:

The ornamental design for a hair band, as shown.

ERNST K. KUENSTNER.
